US00D850290S

(12) **United States Design Patent** (10) **Patent No.:** **US D850,290 S**
Jones et al. (45) **Date of Patent:** **** Jun. 4, 2019**

(54) **CARRIER**

- (71) Applicant: **Meso Scale Technologies, LLC.**, Rockville, MD (US)
- (72) Inventors: **Eric Jones**, Frederick, MD (US); **Jennifer Parker**, Frederick, MD (US); **Manish Kochar**, Rockville, MD (US); **Peter Bosco**, Rockville, MD (US)
- (73) Assignee: **MESO SCALE TECHNOLOGIES, LLC.**, Rockville, MD (US)
- (**) Term: **15 Years**
- (21) Appl. No.: **29/571,996**
- (22) Filed: **Jul. 22, 2016**
- (51) LOC (11) Cl. **09-01**
- (52) U.S. Cl. **USPC D9/751**
- (58) **Field of Classification Search**
